UNITED STATES PATENT OFFICE.

FREDERICK H. HOFFMAN, OF PHILADELPHIA, PENNSYLVANIA, ASSIGNOR TO WILLIAMS, BROWN & EARLE, OF PHILADELPHIA, PENNSYLVANIA, A CORPORATION OF PENNSYLVANIA.

CONTROLLER DEVICE FOR ELECTRIC LIGHTING AND HEATING PURPOSES.

1,221,451.

Specification of Letters Patent.

Patented Apr. 3, 1917.

Application filed March 3, 1916. Serial No. 81,818.

To all whom it may concern:

Be it known that I, FREDERICK H. HOFFMAN, a citizen of the United States, residing at the city of Philadelphia, in the county of 5 Philadelphia and State of Pennsylvania, have invented certain new and useful Improvements in Controller Devices for Electric Lighting and Heating Purposes, of which the following is a specification.

10 My invention relates to a device for controlling two sets of electric circuits arranged for lighting and heating or drying purposes by means of double throw switches, included in one set of said circuits but adapted to be 15 shifted for diverting certain of the current into the other set of said circuits, so that while one set of said circuits is being employed for lighting diverted current therefrom may be utilized in the other set of said 20 circuits in which heating or drying means are included, without interfering with or interrupting the lighting derived through the first named circuit.

An application of such a device is in a 25 combined blue printing, washing and drying machine for economically and expeditiously lighting in blue printing and for diverting certain of the current of said circuits in the blue printing operation to use in a combined washing and drying machine, for hastening drying of prints, the product of such 30 machine, without interfering with continuous blue printing operations in the said machine.

35 In the defined connection my invention stated in general terms, consists of the arrangement of the said device with two sets of electric circuits, with pole switches therein and with double throw knife switches for 40 diverting certain of the current of the said electric circuits for the purposes stated, among other general uses for the same, in heating or drying as well as in lighting electric circuits.

45 The nature and scope of my present invention will be more fully understood from the following description taken in connection with the accompanying drawings forming part hereof, in which—

50 Figure 1, is a diagrammatic view of a controller device for electric lighting and heating circuits, embodying the essential main features of my said invention and showing the double throw knife switches.

Fig. 2, is a plan view of a portion of the 55 interior of the housing of the controller device, showing one of the double throw switches, marked on one side "Lamp" and the other side in dotted outline "Heater" and thus respectively, disclosing how the current can be shifted instantly in a lamp circuit to one in which both lamps and a heater are included.

Fig. 3, is a vertical sectional view on the line x, x , of Fig. 2; and 65

Fig. 4, is an enlarged view of two of the detachable resistance coils of the controller device provided with shiftable spanning strips, the cartridge coils mounted in a housing and so arranged as to be shifted 70 along the coils to instantly vary resistance of the same.

Referring to the drawings 2 is a rectangular-shaped box, in which is arranged a series of binding posts a^1 and a^2 , to which 75 are connected electric circuits 10 and 11, from a source of energy. Within the box are arranged double pole switches 10^a and 11^a as clearly shown in Fig. 1. The posts a^1 and a^2 , are provided with double knife 80 switches b , which are pivoted thereto and arranged to engage either the contacts b^1 and b^2 or b^3 and b^4 , according to the purposes for which the device is to be employed, that is, either in lighting or lamp electric 85 circuits 12—13 or in both lighting or lamp circuits 12—13 and heating or drying circuits 14—15, as clearly shown in Fig. 1. The variable resistance coil rheostat in the form 90 of cartridges c , in the lighting or lamp circuits 12—13, are arranged to the left in Fig. 1, and the heating coils j , to the right in the heating or drying circuits 14—15, in the said figure. The contacts b^1 and b^2 and b^3 and b^4 , respectively, by means of bolts b^6 and nuts 95 b^7 , are connected with contact clips b^5 . These clips form bearings for the rheostat or cartridge coils c , on the reverse side of the box a , as clearly illustrated in Fig. 3. The variable resistance cartridge coils c , removably engage the said clips b^5 , and each pair is provided with a spanning strap c^1 , to couple each with the other. These clips as 100 arranged are readily shiftable along the cartridge coils for instantly if necessary, increasing or decreasing resistance through the same, as will be clearly understood from Fig. 4.

65

70

90

100

105

The variable resistance coils c , are employed to increase or decrease the amperage of the arc lamps employed, for example, in a blue printing machine in which the said controller device as arranged and hereinbefore described is particularly well adapted to be employed economically and efficiently, in conjunction with a combined washing and drying machine, for completing the prints produced and finally drying the same for immediate use. That is to say, in instances where the voltage is entirely too high or too low to instantly rectify the same by the simple shifting of the spanning strap c^1 along the coils c , becoming thereby practically a rheostat. Hence it will be observed that these coils can be employed reliably for adjusting conditions of the arc-lamps where voltage varies from time to time because having the conditions present for readily rectifying the same.

In the operation of the said controller device, the current for lighting alone instead of being entirely and wastefully employed in lamp circuits 12—13 of Fig. 1, may be conserved and utilized by diverting a part of this current and employing it in heating or drying means, included in the said electric circuits 14—15. This is accomplished by simply shifting one or more of the series of double throw switches b , of Fig. 1, so that at one and the same time, the device may be employed for the hereinbefore explained purposes.

Having thus described the nature and objects of my invention, what I claim is:

1. A controller device of the character described, comprising two sets of electric circuits, in one set of which circuits a rheostat is included and in the other set of said circuits, heating or drying means, a series of double throw switches arranged in one set

of said circuits and adapted to be shifted into the other set of said circuits to establish thereby lighting and heating or drying circuits, without interfering with lighting while utilizing the diverted current for heating or drying purposes.

2. A controller device of the character described, comprising two sets of electric circuits, double pole switches therein, a rheostat or cartridge coils, included in one set of said circuits, heater or drying means in the other set of said circuits, a series of double throw switches in one set of said circuits and adapted to be shifted into the other set of said circuits to divert part of the current of said circuits to establish thereby lighting and heating or drying circuits, without interfering with lighting, while utilizing the diverted current, for heating or drying purposes.

3. A controller device of the character described, comprising two sets of electric circuits with double pole switches therein, a rheostat or cartridge coils provided with shiftable bands, included in one set of said circuits, heater or drying means, included in the other set of said circuits and a series of double throw switches arranged in one set of said circuits and adapted to be shifted into the other set of said circuits to establish thereby lighting and heating or drying circuits, without interfering with lighting, while utilizing the diverted current of said circuits, for heating or drying purposes.

In witness whereof, I have hereunto set my signature in the presence of two subscribing witnesses.

FREDERICK H. HOFFMAN.
